UPHOLSTERED CHAIR OR SIMILAR ARTICLE

Israel Sarge Taffae, Cedarhurst, N. Y.

Application January 30, 1953, Serial No. 23,380

Term of patent 3½ years

(Cl. D15—8)

To all whom it may concern:

Be it known that I, Israel Sarge Taffae, a citizen of the United States of America, residing in Cedarhurst, county of Nassau, and State of New York, have invented a new, original, and ornamental Design for an Upholstered Chair or Similar Article, of which the following is a specification, reference being had to the accompanying drawing, forming part thereof.

Fig. 1 is a side elevational view of an upholstered chair or similar article, showing my new design.

Fig. 2 is a rear perspective view thereof.

Fig. 3 is a front perspective view of the chair as illustrated in Fig. 1. The dominant features of the design reside in the full line portions.

I claim:

The ornamental design for an upholstered chair or similar article, substantially as shown and described.

ISRAEL SARGE TAFFAE.
